TWISTING DEVICE

Filed March 23, 1928

INVENTOR
W. J. LEACH

BY *W. J. Leach*

ATTORNEYS

UNITED STATES PATENT OFFICE.

WILLIAM J. LEACH, OF BURLINGTON, WISCONSIN.

TWISTING DEVICE.

Application filed March 23, 1928. Serial No. 264,079.

My invention relates to improvements in twisting devices, and it consists in the combinations, constructions, and arrangements herein described and claimed.

5 An object of my invention is to provide a twisting device in which certain improvements are embodied over the device disclosed in my Patent No. 1,629,800, issued May 24, 1927.

10 A further object is to provide a twisting device which is easy to operate in that the device may be conveniently opened with one hand.

15 A further object is to provide a twisting device in which the body portion is designed in two parts, one of the parts being pivotally mounted with respect to the other, and in which the sockets for receiving the handles of the device are provided in the part supporting the pivotally mounted part, thereby providing a twisting device which is relatively durable and simple in construction.

20 A further object is to provide a twisting device in which the number of hinges is reduced to a minimum.

25 A further object is to provide a twisting device which is rigid, thereby providing a device which is convenient to handle.

30 A further object is to provide a twisting device in which removable dies are provided, and in which the dies are effectively supported in the twisting device so that a maximum amount of power may be applied to the device.

35 Other objects and advantages will appear in the following specification, and the novel features of the invention will be particularly pointed out in the appended claims.

40 My invention is illustrated in the accompanying drawings, forming part of this application, in which

Figure 1 is a side elevation of my device,

Figure 2 is a sectional view taken along the line 2—2 of Figure 1,

45 Figure 3 is a sectional view taken along the line 3—3 of Figure 1,

Figure 4 is a detail view of the ratchet mechanism of my device,

50 Figure 5 is a fragmentary detail view of the device shown in Figure 4, and

Figure 6 is a view showing the application of a pair of my devices preparatory to the twisting of a tube.

55 In carrying out my invention, I make use of a body portion A comprising a section 1 and a section 2 pivotally mounted at 3 upon

the section 1. The section 1 is provided with extended portions 4 having sockets 5 for supporting suitable handles 6.

A suitable spring 7 is provided for actuating the section 2 when a locking device 8 is moved into the dotted line position. When in the dotted line position, the bolt portion 9 of the locking device is entirely withdrawn from an opening 10 in the section 2, thereby 60 freeing the section so that the spring 7 will move the section 2 into the dotted line position shown in Figure 1.

The sections 1 and 2 are provided with a groove 11, see Figures 1 and 2. A ratchet 70 mechanism comprising sections 12 and 13 is mounted within the groove 11. The sections 12 and 13 are substantially identical in construction and are provided with ratchet teeth 14 which are disposed within the groove 11, 75 as shown in Figures 1 and 2.

The sections 12 and 13 are hingedly secured together at 15, as shown in Figure 4, and may be opened up, as shown. The section 12 is provided with a tongue 16 which is 80 arranged to pass into a recess 17 in the section 13 when the two sections are closed, as shown in Figure 1. When in the closed position, the tongue 16 is locked within the recess 17 by means of a spring-pressed pin 18 which passes 85 through an opening 19 in the tongue.

The ratchet mechanism comprising the sections 12 and 13 is adapted to support a die 20 which is made in two parts. In referring to Figure 3, it will be noted that the die 20 is 90 somewhat thinner than the sections 12 and 13 so that grooves 21 may be provided in the latter for supporting the die. The sections of the die 20 are removably supported in the grooves 21. When the sections of the die 20 are disposed in the grooves 21, as shown in Figure 1, the sections are retained in position by means of spring-pressed ball members 22. Suitable recesses are provided in the die 20 for receiving a portion of the ball members 22. 95

The body portion A may be rotated in one direction about the ratchet mechanism, but is locked against rotation with respect to the ratchet mechanism when rotated in the opposite direction. Means for locking the body 100 portion A against rotation with respect to the ratchet mechanism consists of a spring-pressed pawl 23, as shown in Figure 1. The die 20 is provided with intersecting openings 24 through which a tube 25 containing cables 105 26 may be disposed.

From the foregoing description of the va-

rious parts of the device, the operation thereof may be readily understood. In Figure 6, I have shown a pair of twisting devices B and C mounted upon the tube 25. When the body portion A is mounted upon the tube 25, the locking device 8 is moved into the dotted line position, whereupon the section 2 will be moved into the dotted line position by means of the spring 7. At this time the ratchet mechanism comprising the sections 12 and 13 may be opened by pulling the pin 18 so as to free the tongue 16.

Since the die 20 is of a two-piece construction, the die will of course open with the sections 12 and 13, as shown in Figure 4, whereupon the tube twister may be applied to the tube 25. After the twisting device has been applied to the tube, the ratchet mechanism is closed and locked by means of the pin 18 and the section 2 is moved down upon the ratchet mechanism and locked by moving the locking device 8.

It will be noted that a slight rotation of the handles about the transverse axis of the device will cause the ratchet mechanism to rotate in one direction step by step. Thus it will be seen that I have provided a twisting device which may be effectively used for twisting a tube that is disposed relatively near a second tube or cable. When twisting the tube 25, a pair of devices is employed, as shown in Figure 6. The individual devices when so mounted will be rotated in opposite directions, or one of the devices may be held stationary and the other rotated.

The present invention provides a device which is convenient to handle, particularly when working in inconvenient places. The body portion of the device is rigid and the device can be opened with one hand. Further than this, I have provided a device in which the die may be easily removed without the use of screw drivers and the like. The die may be quickly changed for other dies and when the die is disposed in place, it is firmly secured. The spring-pressed ball members 22 permit the two sections of the die 20 to be pulled out by the hand.

I claim:

50. 1. A twisting device comprising a ratchet mechanism, a body portion mounted for rotation about the transverse axis of said ratchet mechanism, said body portion comprising a pair of sections, one of said sections being hingedly mounted upon the other section, means carried by the body portion for engaging the ratchet mechanism for locking the body portion against rotation in one direction with respect to said ratchet mechanism, said ratchet mechanism comprising a pair of hinged-together sections, a die removably carried by the ratchet mechanism, and ball means for removably supporting said die within the ratchet mechanism.

65. 2. A twisting device comprising a ratchet

mechanism, a body portion mounted for rotation about the transverse axis of said ratchet mechanism, said body portion comprising a pair of sections, one of said sections being hingedly mounted upon the other section, means carried by the body portion for engaging the ratchet mechanism for locking the body portion against rotation in one direction with respect to said ratchet mechanism, said ratchet mechanism comprising a pair of hinged-together sections, a die removably carried by the ratchet mechanism, and ball means for removably supporting said die within the ratchet mechanism, said die comprising a pair of sections arranged to be individually removed from said ratchet mechanism.

3. A twisting device comprising a ratchet mechanism, a body portion mounted for rotation about the transverse axis of said ratchet mechanism, said body portion comprising a pair of sections, one of said sections being hingedly mounted upon the other section, means carried by the body portion for engaging the ratchet mechanism for locking the body portion against rotation in one direction with respect to said ratchet mechanism, a die removably carried by the ratchet mechanism, means for locking the hingedly-mounted section with respect to the other section, and means for automatically swinging the hingedly-mounted section away from the other section when said named means is unlocked.

4. A twisting device comprising a ratchet mechanism, a body portion mounted for rotation about the transverse axis of said ratchet mechanism, said body portion comprising a pair of sections, one of said sections being hingedly mounted upon the other section, means carried by the body portion for engaging the ratchet mechanism for locking the body portion against rotation in one direction with respect to said ratchet mechanism, a die removably carried by the ratchet mechanism, means for locking the hingedly-mounted section with respect to the other section, means for automatically swinging the hingedly-mounted section away from the other section when said last named means is unlocked, and a pair of arms secured to one of said sections.

5. A twisting device comprising a body portion having a pair of sockets, a movable body portion carried by said first-named body portion, a locking mechanism for locking the movable body portion with respect to the first-named body portion, spring means for moving the movable body portion away from the first-named body portion when the said locking device is released, a ratchet mechanism associated with said first and second-named body portions, and a die slidably removable from said ratchet mechanism.

6. A twisting device comprising a ratchet

- mechanism, a body portion mounted for rotation about the transverse axis of said ratchet mechanism, said body portion comprising a pair of sections, one of said sections being hingedly mounted upon the other of said sections, a die associated with said ratchet mechanism and being slidably removable therefrom, and a pair of handles secured to one of said body portions.
- 10 7. A twisting device comprising a ratchet mechanism, a body portion mounted for rotation about the transverse axis of said ratchet

mechanism, said body portion comprising a section having sockets and a section hingedly mounted upon the other section, said ratchet mechanism comprising a pair of hinged together sections, a die removably carried by the ratchet mechanism, and means for removably supporting said die within the ratchet mechanism.

Signed at Burlington, in the county of Racine and State of Wisconsin, this 19th day of March, A. D. 1928.

WILLIAM J. LEACH.
